ALEXANDER CARNEGIE KIRK, OF GLASGOW, GREAT BRITAIN.

Letters Patent No. 84,428, dated November 24, 1868.

IMPROVEMENT IN BLOWING-ENGINES.

The Schedule referred to in these Letters Patent and making part of the same.

To all whom it may concern:

Be it known that I, ALEXANDER CARNEGIE KIRK, of Glasgow, in the county of Lanark, Kingdom of Great Britain and Ireland, have invented a new, useful, and improved Blowing-Engine; and I do hereby declare the following to be a full, clear, and exact description of the same.

My invention consists in adapting to a horizontal cylinder a hollow piston, fitted with valves, and fixed on and supported by a trunk or hollow piston-rod, the whole being constructed and operating as fully described hereafter, so as to draw air or gas through the trunk and piston, and expel it through the cylinder-valves, or *vice versa*.

In order to enable others skilled in the art to make and use my invention, I will now proceed to describe its construction and operation, reference being had to the accompanying drawing, which forms a part of this specification, and in which—

Figure 1 is a vertical section of my improved blowing-engine, and

Figure 2, an end view, partly in section.

The engine consists of a cylinder, 1, with ends or covers, 2, formed with valve-openings, and fitted with valves, 3.

The cylinder-ends 2 are also formed with ordinary stuffing-boxes, for the passage of a hollow trunk, 4, upon which is fixed a hollow piston, A, consisting of two disks, 5, disposed a short distance apart.

The piston-disks 5 are formed with valve-openings, and are fitted with valves, 6, and these valves, as well as those, 3, in the cylinder-ends, are represented as arranged for drawing in the air through the trunk 4 and piston 5, and expelling it through the cylinder-ends into casings, 7, formed upon the cylinder-ends, and communicating, by branch-passages 8, with the main, 9, by which it is led away for use.

To admit the air into the trunk 4, openings, 10, are formed at or near the opposite ends of it, the trunk

being sufficiently long for these openings to be always beyond the cylinder stuffing-boxes. Openings, 11, are also formed in the trunk 4, at its middle, to admit the air into the space between the piston-disks 5.

At the ends the trunk has fixed upon it cross-heads, 12, which rest and slide upon guide-bars, 13, fixed upon the masonry or foundation, and by these means the weight of the trunk and piston is effectually borne up, so as to prevent the injurious rubbing of the piston on the bottom side of the cylinder.

The piston-disks 5 are represented as fitted with ordinary cupped leather packings, and the valves as made of leather in the ordinary way; but these, as well as other minor details, may, of course, be varied according to the views of those making the engine.

The trunk 4 is represented as having attached to one end of it a portion of the piston-rod 14, of a horizontal-cylinder steam-engine, by which it is supposed to be actuated.

If it is wished to deliver the air from the trunk 4, instead of drawing it in thereby, one or both ends thereof must be arranged to work through stuffing-boxes into closed receiver's or delivery-passages.

I claim as my invention, and desire to secure by Letters Patent—

The cylinder 1, with its openings and valves, in combination with casings 7 7, and with a hollow piston-rod or trunk extending through both heads of the cylinder, open at each end, and communicating with a hollow piston, A, having openings and valves arranged as described, the whole being constructed and operating as set forth.

In testimony whereof, I have signed my name to this specification, in the presence of two subscribing witnesses.

ALEXANDER C. KIRK.
